(57) **CLAIM**

The ornamental design for spring device, as shown and described.

DESCRIPTION

FIG. 1 is an isometric view of the spring device shown in a free state configuration, according to the disclosed subject matter

FIG. 2 is a top view of the spring device of FIG. 1.

FIG. 3 is a bottom view of the spring device of FIG. 1.

FIG. 4 is a left side view of the spring device of FIG. 1.

FIG. 5 is a right side view of the spring device of FIG. 1.

FIG. 6 is a front view of the spring device of FIG. 1.

FIG. 7 is a back view of the spring device of FIG. 1.

FIG. 8 is an isometric view of the spring device of FIG. 1 shown in a compressed configuration, according to the disclosed subject matter.

FIG. 9 is a top view of the spring device of FIG. 8.

FIG. 10 is a bottom view of the spring device of FIG. 8.

FIG. 11 is a left side view of the spring device of FIG. 8.

FIG. 12 is a right view of the spring device of FIG. 8.

FIG. 13 is a front view of the spring device of FIG. 8.

FIG. 14 is a back view of the spring device of FIG. 8; and, FIG. 15 is a perspective view of the spring device in the free state configuration coupled with a drop wire clamp and a span clamp.

The broken lines of FIG. 1-FIG. 15 depict portions of the spring device in which the design is embodied that are not considered part of the claimed design. The broken lines of FIG. 15 showing an environmental structure of the spring device form no part of the claimed design.

1 Claim, 9 Drawing Sheets
